TENSION CONTROLLING MECHANISM

Paul L. Tollison, North Plainfield, N. J., and Charles S. Caffrey, Port Washington, N. Y., assignors to Wood Newspaper Machinery Corporation, Plainfield, N. J., a corporation of Virginia

Application April 22, 1939, Serial No. 269,380

2 Claims. (Cl. 242—75)

This invention is particularly adapted for controlling the tension of a printing web which is being fed to a printing press.

The principal objects of the invention are to provide an efficient means for maintaining a constant web tension when the running roll is moved into the tension belts or any other means provided for controlling the tension of the web; to provide a device of this character which will compensate for the various tensions and regulate the tension in accordance therewith but keep the tension substantially constant, and to contemplate compensation for web tension changes created by the motion of the roll handling mechanism regardless of the type of roll carrier or character of tensioning means employed.

The application of the invention is not limited to the particular type of newspaper feeding devices shown in the drawings in which the tension belts are in a position to engage the feeding web roll and toward which that roll is moved during the feeding operation. The manner of applying the tension depends, of course, on whether the tension control is mechanical, electrical or fluid pressure.

Other objects and advantages of the invention will appear hereinafter.

Reference is to be had to the accompanying drawings, in which

Fig. 1 is an end view showing the parts for regulating the tension of the web;

Fig. 2 is a side view of a tension regulating mechanism showing the magnetic clutch in section;

Fig. 3 is a plan of a portion of the same;

Fig. 4 is a view similar to a part of Fig. 1 on enlarged scale and showing the holding means for the top of the friction belts in a clearer manner, and

Fig. 5 is a wiring diagram of the reel and tension weight lifting clutch.

In Fig. 1 a reel stand 1 rotatably mounts a reel shaft 2 to which end spiders 3 are secured. Said spiders support the expiring web roll 4 and the new roll 5. The web 6 from the roll 4 passes around a bending roller 8, tension roller 9, and bending rollers 10 and 11 into the press. Rollers 8, 10 and 11 have a fixed position and tension roller 9 is movable.

Tension belts 1 are anchored at their lower end and are arranged in such manner that they will contact the paper rolls as shown in Fig. 1. The belt is then continued over pulleys 12, 13 and 14 and is secured at its end by a tension belt anchor 15. The pulley 14 is movable.

The rotation of the reel shaft 2 causes a sprocket wheel 16 secured thereon to move a chain 17 and consequently turn a sprocket 18 which is secured to a hub 20. The hub 20 is loosely mounted on a shaft 19 and has a clutch plate 21 fastened to it. Rotation of the reel shaft 2, therefore, causes the clutch plate 21 to rotate.

A magnetic clutch body 22 and sprocket wheel 23 are securely fastened to the shaft 19. The energizing of the clutch body 22 will cause it to become engaged with the clutch plate 21 and complete magnetic and mechanical connection from the reel shaft 2 to the sprocket wheel 23, resulting in a tendency to rotate said sprocket wheel, depending upon the strength of the magnetic clutch 22 whenever the reel shaft 2 is rotated and the clutch 22 is energized.

The energizing of the clutch 22 is best illustrated by the wiring diagram of Fig. 5. The depressing of a button 24 on the control panel will complete a circuit through 25 and 28, to the forward operating solenoid 26. The line 25 is connected to the reel panel where it may be traced to a forward operating solenoid 26 whose other side is 27, then continues into an overload relay where it becomes 40, then through to the main line L2. The line 28 on the opposite side is wired to the panel where it may be traced directly to the line L2.

A solenoid 33 is connected in parallel with the solenoid 26 by a wire 27. Line 25 will be the opposite side of the solenoid 33. In this manner the solenoids 33 and 26 will be energized at the same time. The solenoid 26 controls the forward contactors and, when closed, sets motor 37 into operation. The solenoid 33 closes contact 34 which completes the direct current circuit through the tension weight lifting clutch 22. A rheostat 36 connected into the line may be used to regulate the voltage passing through the clutch 22. A limit switch 35 is placed in the circuit.

It is therefore evident that forward rotation of the reel and clutch excitation at the same time will cause the sprocket wheel 23 to revolve.

An autopaster attached to a reel will have certain electrical controls added to move the reel forward automatically after a splice has been completed. Means, not shown on the wiring diagram, would energize the solenoid 26 and consequently the solenoid 33 at a predetermined position in the pasting cycle. The result would be the forward rotation of the reel and the excitation of the clutch 22.

A tension weight 42 releasably secured to an

arm, on a shaft 41, urges said shaft to turn in a counter clockwise manner, carrying with it a lever 43. To the hub of the lever 43 is attached a sprocket 40 connected to the sprocket 23 by the chain 77. A stud 44 mounted in the outer end of the lever 43 supports one end of a connecting link 45. The other end of said link is attached to a shaft 49, carried in a lever 46, by a stud 47 in such manner that it will allow the lever 46 to oscillate about a stud 48 which is secured in the machine frame.

A shaft 49 and poppet 50, supported thereby, are mounted in the outer end of the lever 46. The shaft 49 carries the roller 14 which is held in location by guide collars 51 and 52. The shaft 49 carries one end of a spring rod 53 whose shank passes through a poppet 54 located in an anchor shaft bracket 55. A spring 56, carried on the rod 53, is held in compression against said poppet by an adjusting collar 57 fastened on the rod 53 and will take up any lost motion when said rod is moved through the poppet 54.

The poppet 50 carries the shank of a spring rod 58 which is secured to the tension roll lever 59 by a stud 60. A spring 61 held against the poppet 50 by a collar 62 urges the tension roll lever 59 to turn in a counter-clockwise manner about a shaft 63. The web 6, which turns around the roll 9 that is carried at the outer end of the lever 59, produces a pull on said roll in opposition to the action of the spring 61. Slight variations in web tension will be compensated by the above spring.

The tension belt 7 that passes around the roller 14 is held by the anchor 15 to the anchor lever 64 by means of the poppet 65 and is adjustable in said poppet by check-nuts 66 and 67. The lever 64 is pinned to a shaft 68 that is rotatably mounted in a bracket 55, and a pin 69, fixed in said bracket. This limits the shaft rotation by its cooperation with a slot 70 machined in a lever 71 which is secured to the shaft 68. This is best seen in Fig. 3.

Referring again to Fig. 1, it will be noted that the tension weights 42 will move all parts connected to the tension belt roll lever 46 to the left and by drawing the belts 7 to the left will turn the shaft 68 in a counterclockwise manner until one side of the slot 70 comes against the pin 69 and stops further motion of the belt anchors. This same rotation will carry a spring pin 72 against the pin 69 and will compress a spring 73 carried in a hole 74, which is made for that purpose in the lever 71. Slack in the tension belts will cause the spring 73 to turn the anchor lever 64 and consequently the lever 71 in a clockwise direction until again stopped by the pin 69. This motion will carry a set screw 75 held in the end of the lever 71 to move against a roller 76 in the limit switch 35 and open the circuit therein.

It is now evident that rotation of the reels into the belts 7 will produce the following action:

The excitation of the reel motor for forward motion will also energize the clutch 22 and establish a connection between the reel shaft 2 and the sprocket 23.

The sprocket 23 is connected to the weight lifting mechanism by the chain 77 and will tend to move the weights in a clockwise manner when the reel moves forward. This will move all tension parts to the right and decrease the tension on the paper rolls. If too much weight is relieved, allowing too much slack, the spring 72 will func-

tion and rotate the lever 71 and the set screw 75 against the roller 76 of the limit switch 35 and will interrupt the direct current circuit to the magnetic clutch 22 thereby deenergizing this unit and allowing the tension weights to function in a normal manner. Movement of the set screw 75 upwardly will release the roller 76, causing the limit switch 35 to close the circuit. The rheostat 36 can be adjusted to allow less torque than is required for the weights to be raised to produce the proper degree of tension so that limit switch 35 may remain closed at all times. Used in that manner the switch 35 merely becomes a safety.

When using half rolls it is customary to reduce the number of tension weights and under this condition the web 6 may exert sufficient pull to raise the tension roll 9 upward beyond its normal position assumed when operating with a full roll. Additional web strain may cause the half roll to overcome the efforts of the tension weights and the paper may run loose, because the tension weights would be using up part of their force in returning the tension roller to the proper position.

The spring 56, which was previously described, will now function to counteract the additional burden placed on the tension weight by the overbalancing of the roller 9 and will cause the tension parts to resume their normal position.

That a suitable and efficient means for controlling paper tension when rotation of the reel is necessary is now obvious. This device will compensate for various conditions and regulate the tension accordingly. The scope of this invention is not limited to the particular form shown but contemplates compensation for web tension changes created by the motion of roll handling mechanisms regardless of the type of roll carrier or character of tensioning means employed.

Having thus described our invention and the advantages thereof, we do not wish to be limited to the details herein disclosed, otherwise than as set forth in the claims, but what we claim is:

1. The combination with means for supporting a web supply roll, means for feeding the web from said roll to a press, or the like, and tension belts for engaging the web on said roll, of a web tension weight, a magnetic clutch adapted to be clutched with respect to the weight when the magnet is energized, means cooperating with the clutch for turning it on its axis, a wheel adapted to turn with the weight when the clutch is in operative condition, said weight being connected to the axis of said wheel and depending at an angle to the vertical and mechanical means for turning the wheel to vary the tension.

2. The combination with means for supporting a web supply roll, and tension belts for engaging the web on said roll, of a web tension weight, a magnetic clutch adapted to be clutched with respect to the weight when energized, means cooperating with the clutch for turning it on its axis, a wheel adapted to turn with the weight when the clutch is in operative condition, said weight being connected to the axis of said wheel and depending at an angle to the vertical and means turning with the wheel to vary the tension to compensate for any movement of the web roll into the tension belts.
